SWITCH & SIGNAL COMPANY, OF SWISSVALE, PENNSYLVANIA, A CORPORATION
OF PENNSYLVANIA.

SIGNAL.

1,227,778.

Specification of Letters Patent.

Patented May 29, 1917.

Original application filed January 20, 1914, Serial No. 813,157. Divided and this application filed January 18, 1917. Serial No. 143,091.

To all whom it may concern:

Be it known that I, ROBERT M. GILSON, a citizen of the United States, residing at Pittsburgh, in the county of Allegheny and 5 State of Pennsylvania, have invented certain new and useful Improvements in Signals, of which the following is a specification.

My invention relates to signals and particularly to signals of the type in which a source of light is employed for giving indications both at night and in daylight. Signals embodying my invention are particularly adapted for use in railway signaling, 10 although they are not limited to this particular adaptation. When a signal of the type mentioned is used on a railway curve, the beam of light projected by the signal should be visible over all points on the curve 15 in the rear of the signal. Hence, this beam is preferably elongated in a horizontal direction, but not in a vertical direction. Furthermore, it is desirable that the beam should appear to be about of the same intensity 20 from all points on the curve, hence the beam preferably varies progressively in intensity from a maximum value adjacent one end to a minimum value adjacent the other, the more intense portion of the light 25 being directed toward the end of the curve farthest from the signal and the less intense portions being directed toward the sections of the curve nearer to the signal. One feature of my invention is the provision of a 30 signal which will project an elongated beam of light which varies progressively in intensity from the maximum value adjacent one end to a minimum value adjacent the other.

40 The present application is a division of my copending application filed January 20, 1914, Serial No. 813,157, for signals.

I will describe one form of signal embodying my invention, and will then point 45 out the novel features thereof in claims.

In the accompanying drawings, Figure 1 is a top view showing one form of signal embodying my invention. Fig. 2 is a view on an enlarged scale showing in detail one set 50 of dimensions which may be employed for each of the prismatic corrugations 14 of the screen 12 shown in Fig. 1, to obtain a certain degree of elongation of the beam projected thereby, and to cause variation of the intensity of the beam according to a certain 55 curve. Fig. 3 is a curve showing the intensity of light at the various points along the line III—III of Fig. 1. Fig. 4 is a view showing a railway curve provided with a signal embodying my invention, and designating the portions of the curve toward 60 which are directed the several parts of the beam indicated by the zones in Fig. 3.

Similar reference characters refer to similar parts in each of the several views. 65

Referring first to Fig. 1, the signal here shown comprises an incandescent lamp 10 from which a beam of light comprising substantially parallel rays 13 is projected by a lens 11. Although I have shown an incandescent lamp as the source of light, it is understood that any other suitable source may be employed; and although I have shown a lens, it is understood that any other suitable means may be employed for projecting a 70 beam of substantially parallel rays from the source 10.

Located in the path of the beam 13 is a glass screen 12 which is adapted to elongate the beam horizontally, and to cause its intensity to vary progressively from a comparatively high value adjacent one end to a comparatively low value adjacent the other. As here shown, this screen comprises a plurality of vertically disposed parallel prismatic corrugations 14, which corrugations I will hereinafter refer to as "prisms." The inclined face of each prism is concaved substantially as shown, so that the angle of refraction varies by small increments from a 80 minimum value adjacent one edge of the prism to a maximum value adjacent the other edge. This variation is illustrated by the lines 15, which indicate the directions of the rays emerging from the various parts of the prism. It will be seen that the beam projected from each prism is therefore elongated along the line III—III. Each prism is furthermore designed so that the intensity 85 of the beam emerging therefrom varies from a maximum value adjacent the edge having the smallest angle of refraction to a minimum value adjacent the edge having the greatest angle of refraction, so that the variation of intensity, along the line III—III, 90 of the beam from each prism is substantially as indicated by the curve in Fig. 3. Inasmuch as all of the prisms 14 are alike, the

95 100 105

curve in Fig. 3 also indicates the variation in intensity along the line III—III of the beam emerging from the signal as a whole.

In Fig. 2 I have shown in detail one of the prisms 14, together with the exact dimensions which may be employed to give a spread of approximately 15° and to cause the variation of intensity indicated by the curve in Fig. 3. It will be seen that the rays 15 from each prism intermingle with those from the other prisms, resulting in a smooth curve of variation of intensity such as that shown in Fig. 3.

In Fig. 4 I have shown a railway curve 15 F, at one end of which is a signal S, such as is shown in Fig. 1, and which projects a horizontally elongated beam varying in intensity substantially as indicated by Fig. 3. Signal S is so located that the portion 20 A of the beam projected by the signal is directed toward section A' of the curve, portion B toward B', etc. That is, the most intense portion of the beam is directed toward the section of the curve farthest 25 from the signal, and the portions of the beam of progressively decreasing intensity are directed toward the sections of the curve progressively approaching the signal. Hence, as an observer passes along the curve 30 F toward the signal, the beam of light is constantly visible, and constantly appears of substantially the same intensity. There is, therefore, no light wasted in unnecessarily intense illumination at any one part 35 of the curve.

Although I have herein shown only one form of signals embodying my invention, it is understood that various changes and modifications may be made therein within 40 the scope of the appended claims without departing from the spirit and scope of my invention.

Having thus described my invention, what I claim is:

45 1. A signal adapted for use on a railway curve and comprising a source of light, means for projecting from said source a beam of substantially parallel rays, and a glass screen located in said beam and comprising a series of vertically disposed prisms, the angle of refraction of each of which prisms increases progressively from a minimum value adjacent one side of the prism to a maximum value adjacent the 50 other, said beam-projecting means and said screen being so placed that the portions of 55

the beam which are deflected through the greatest angle are directed toward one end of the curve and the portions of the beam which are deflected through the least angle 60 are directed toward the other end of the curve.

2. A signal adapted for use on a railway curve and comprising a source of light, means for projecting from said source a beam of substantially parallel rays, and a glass screen located in said beam and comprising a series of vertically disposed prisms, the angle of refraction of each of which prisms increases progressively from a minimum value adjacent one side 70 to a maximum value adjacent the other, and the intensity of the beam emerging from each prism varying progressively from a maximum value adjacent one side 75 to a minimum value adjacent the other side, said beam projecting means and said screen being so located that the portion of the beam having the highest intensity is directed toward the far end of the curve and the portion of the beam having the lowest intensity is directed toward the part of the curve 80 nearest to the signal.

3. A signal comprising a source of light, means for projecting from said source a beam of substantially parallel rays and a glass screen located in said beam and comprising a series of vertically disposed prisms the angle of refraction of each of which prisms increases progressively from a minimum value adjacent one side of the prism to a maximum value adjacent the other side. 85

4. A signal comprising a source of light, means for projecting from said source a beam of substantially parallel rays and a glass screen located in said beam and comprising a series of vertically disposed prisms the angle of refraction of each of which prisms increases progressively from a minimum value adjacent one side of the prism to a maximum value adjacent the other side, and the intensity of the beam emerging from each prism varying progressively from a maximum value adjacent one side to a minimum value adjacent the other side. 95

In testimony whereof I affix my signature in presence of two witnesses.

ROBERT M. GILSON.
